ATTORNEY

UNITED STATES PATENT OFFICE

JOSEPH P. GARDNER, OF HAMILTON, OHIO

NURSING BOTTLE

Application filed August 28, 1928. Serial No. 302,580.

This invention relates to a nursing bottle, the primary object of which is to so construct a bottle of this character that air will enter at the bottom instead of at the top of 5 the bottle thus causing an easy flow of milk or other contents from the bottle through the nursing nipple and will prevent the child from sucking air through the nipple.

Another object of the invention is to so 10 construct a bottle of this character that there will be no leakage of milk through the valve.

In carrying out these objects, the invention is susceptible of a wide range of modification without departing from the spirit or sacrificing any of the advantages of the claimed 15 invention; there being shown in the drawings for illustrative purposes a preferred and practical form, in which:

In the drawings:

20 Figure 1 represents a perspective view looking upward from the bottom of a bottle constructed in accordance with this invention;

Fig. 2 is a detailed vertical section through the bottom of the bottle showing the improved air inlet;

Fig. 3 is an enlarged detailed sectional view through the valve; and

Fig. 4 is a horizontal section taken on the line 4—4 of Fig. 3.

30 In the embodiment illustrated a bottle 1 of glass is shown and which may be of any desired configuration; having the usual neck 2 and beaded mouth 3 to receive the nursing nipple. The bottom 4 of this bottle has an opening 5 preferably arranged centrally thereof and around which and extending into the bottle is a collar 6 here shown made truncated cone-shaped and which is designed to receive a correspondingly shaped rubber cork 7.

40 The cork 7 has a central opening 4 extending longitudinally through the center thereof and which has an aluminum valve mounted therein and removable with the cork. This valve 10 includes a bevelled disc 11 adapted to seat on the upper end of a sleeve 12 mounted in the bore 8 of the cork 7. A stem 13 depends from the lower face of the valve 10 and extends through and is slidable in a block-like member 14 formed integral 45 with the valve casing 12. Within the block

14 is a socket 15 having a shoulder 16 at its inner end against which bears one end of a coiled spring 17 mounted on the valve stem, the other end of said spring bearing against a stop 18 carried by the outer end of the valve 55 stem and which is adjustable to vary the tension of the spring. It is of course understood that this spring holds the valve disc 11 seated and yet permits said valve to move inwardly against the tension of the spring when the 60 child is sucking the nipple thereby drawing in air through the valve at the bottom of the bottle, air being admitted through bores 19 formed in the block 14. It is of course understood that the spring 17 must be made of 65 non-corrosive steel even though there is no leakage of liquid through the valve which the air in the bottom of the bottle prevents.

This bottle admitting air at the bottom instead of at the top will prevent air colic. 70

When the bottle is to be cleaned the cork 7 may be readily removed and water passed freely through the bottle to cleanse it in all parts thereof.

Without further description it is thought that the features and advantages of the invention will be readily apparent to those skilled in the art, and it will, of course, be understood that changes in the form, proportion and minor details of construction may be 75 resorted to, without departing from the spirit of the invention or its scope as claimed.

I claim:

1. A nursing bottle having an opening in the bottom thereof with a collar surrounding said opening and extending into said bottle, a cork for said collar seating therein and having a central opening with a valve casing located therein, an inwardly opening valve carried by said casing with means for admitting air through said casing to the interior of the bottle on the opening of the valve and a spring for normally holding the valve seated. 85

2. A nursing bottle having an opening in the bottom thereof, a cork for closing said opening, said cork having an opening therein with a valve casing located in said opening, a block-like member in said casing having air passages extending therethrough and provided with a socket having a shoulder at its 90

95

100

inner end, a valve stem extending through the socket in said block and provided at its outer end with an inwardly opening valve and at its other end with a stop, and a coiled spring on said stem within said socket bearing at one end against said shoulder and at its other against said stop for normally holding the valve seated.
